UNITED STATES PATENT OFFICE

120,018

DESIGN FOR A COUNTER OR SIMILAR ARTICLE

Albert Bernhard Remler, Savannah, Ga.

Application December 20, 1939, Serial No. 89,049

Term of patent 3½ years

To all whom it may concern:

Be it known that I, Albert Bernhard Remler, a citizen of the United States, residing at Savannah, in the county of Chatham and State of Georgia, have invented a new, original, and ornamental Design for a Counter or Similar Article, of which the following is a specification, reference being had to the accompanying drawing, forming part thereof.

I claim:

The ornamental design for a counter or similar article, as shown.

ALBERT BERNHARD REMLER.
